ILLUMINATED TABLE

Russell H. McCullough, Los Angeles, Calif., assignor to Fox West Coast Theatres Corporation, Los Angeles, Calif., a corporation of Delaware

Application January 3, 1948, Serial No. 401

2 Claims. (Cl. 240—4)

1

The present invention relates to an illuminated dressing table especially useful in women's powder rooms of a theatre or other public building.

An object of the present invention is to provide an improved cosmetic table artistic in appearance and yet well illuminated by indirect lighting effects.

Another object of the present invention is to provide an improved table essentially of transparent material behind which light sources produce indirect light effects.

Still another object of the present invention is to provide an improved table incorporating a mirror which is illuminated in a new and novel manner.

Still another object of the present invention is to provide improved lighting effects by a tubular light source extending parallel to a plurality of transparent tubular members.

Yet another object of the present invention is to provide an improved illuminated table characterized by the novel manner in which component members thereof are assembled.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is a view in front elevation of three sections of a dressing table embodying the present invention.

Figure 2 is a sectional view taken substantially on the line 2—2 of Figure 1.

Figure 3 is a sectional view taken substantially on the line 3—3 of Figure 2.

Although I have shown the dressing table as having three sections in Figure 1, it is apparent that the table may comprise but one section or more than the exact number shown.

Each section of the table comprises a centrally located plane elliptically-shaped mirror 10 behind which four tubular light sources 11 are disposed; a frosted glass shelf member 12 under which three tubular light sources 13 are disposed; a pair of cylindrically-shaped illuminated towers 14 in each of which there is a centrally located longitudinally extending light source 15, and a pair of urn-shaped members 37 within which a light source may be present.

The manner in which the light sources 13 and 15 are encased to produce a unique lighting effect

5 forms an important feature of the present invention and consists simply of a plurality of transparent rods 20 and 21, respectively, arranged in the arc of a circle in abutting relationship to enclose such tubular members 13 and 15. These transparent rods 20 and 21 preferably are held at their ends as shown in Figure 3 in the pair of spaced channel members 23 and 24. The enclosing members 20 and 21 either may be transparent or translucent depending upon the lighting effect desired.

10 The mirror 10 is spaced away from its decorative supporting wall 30 between which the light sources 11 are located. The mirror 10 may be either fully silvered or partially silvered to allow some light transmission therethrough. In either case, most of the light from the source 11 serves to illuminate the decorative wall 30 thereby to produce a "soft" background for the mirror 10.

15 The wall 30 may extend below the shelf 12 if desired or it may terminate at the shelf 12. The composite table may be supported on the decorative cylindrical legs 35 forming a prolongation of the illuminated towers 14.

20 Although all of the essential elements of the table are supported on the wall member 30 and legs 35, preferably the wall member 30 is secured to the wall of a room to stabilize the position of the table.

25 Each one of the towers 14 may terminate in a metal cylindrical decorative element 36 on top of which is a metal urn 37 in which there may be a concealed light source for throwing a beam of light directly on the ceiling of a room in which the table is placed.

30 Preferably, light sources 13 and 15 are tubular in form similar to the type used to illuminate present-day display showcases.

35 An important feature is the ease with which access may be had to the light source to move and replace the same in the event that the filaments thereof become expended. In such case, it is essential only that the cylindrical metal members be removed. These cylindrical members 36 are fastened to the metal ring 40 by semi-permanent fastening means such as screws 41 which may be easily removed to allow the members 36 and the urns 37 superimposed thereon to be raised upwardly to allow access to the light source 15 therein.

40 In the event that a light source is mounted in the urn 37, flexible electrical conducting leads connected thereto are of sufficient length to allow the limited movement necessary for access to the light source 15.

45 Access may be had to the light source 13 by

either removing the ground glass top 12, or in some cases, removing some of the enclosing members 20.

Access may be had to the light source 11 inasmuch as mirror 10 is spaced a substantial distance from the decorative wall 30.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. A cosmetic table comprising a mirror mounted thereon in a substantial vertical plane, light sources directly behind said mirror, said table having a ground glass top member, a light source below said ground glass top, lighting towers on opposite sides of said mirror extending vertically adjacent said mirror, said light source below said

glass top being encased by a plurality of rods extending generally upwardly, a tubular light source in said towers, said lighting towers comprising a plurality of transparent rods arranged on the arc of a circle with adjacent rods abutting and with their axes extending substantially parallel to the axis of said tubular light source.

2. The structure defined in claim 1, with an L-shaped member having a light source thereon mounted above said lighting tower.

RUSSELL H. McCULLOUGH.
